(57) **CLAIM**

The ornamental design for a combination tandem axle wheel chock and trailer tongue stand, as shown and described.

DESCRIPTION

FIG. 1 is a perspective view of a combination tandem axle wheel chock and trailer tongue stand embodying our design, with the projections on the tire-engaging surface, the ground-engaging flange, the internal and external spacing ribs, and a number of other constructional details being shown in broken lines for illustrative purposes only and forming no part of the claimed design;

FIG. 2 is a top plan view of the combination tandem axle wheel chock and trailer tongue stand depicted in FIG. 1;

FIG. 3 is a side elevation view of the combination tandem axle wheel chock and trailer tongue stand depicted in FIG. 1, with the opposite side elevation being a mirror image thereof;

FIG. 4 is an end elevation view of the combination tandem axle wheel chock and trailer tongue stand depicted in FIG. 1, with the opposite end elevation view being a mirror image thereof; and,

FIG. 5 is a bottom view of the combination tandem axle wheel chock and trailer tongue stand depicted in FIG. 1.
